UNITED STATES PATENT OFFICE

160,348

NEEDLE THREADING DEVICE

Donald M. Stadd, New York, and John M. Sniffen,
White Plains, N. Y.; said Stadd assignor to said
Sniffen

Application May 16, 1949, Serial No. 2,684

Term of patent 3½ years

(Cl. D3—19)

To all whom it may concern:

Be it known that we, Donald M. Stadd and John M. Sniffen, citizens of the United States, respectively residing at New York, in the county of New York, State of New York, and White Plains, in the county of Westchester, State of New York, have invented a new, original, and ornamental Design for a Needle Threading Device, of which the following is a specification, reference being had to the accompanying drawing, constituting a part hereof.

Fig. 1 is a perspective view of the needle threading device, showing our new design.

Fig. 2 is a top plan view.

Fig. 3 is a side elevational view.

Figs. 4 and 5 are respectively opposite end elevational views.

We claim:

The ornamental design for a needle threading device, substantially as shown.

DONALD M. STADD.

JOHN M. SNIFFEN.
